UNITED STATES PATENT OFFICE.

AUGUSTUS BEAN, OF CONCORD, NEW HAMPSHIRE.

IMPROVEMENT IN PORTABLE FURNACES.

Specification forming part of Letters Patent No. 152,033, dated June 16, 1874; application filed April 16, 1874.

To all whom it may concern:

Be it known that I, AUGUSTUS BEAN, of Concord, in the county of Merrimac and State of New Hampshire, have invented certain new and useful Improvements in Portable Furnaces or Attachment for Cooking-Stoves; and I do hereby declare that the following is a full, clear, and exact description thereof, which will enable others skilled in the art to which it appertains to make and use the same, reference being had to the accompanying drawings and to the letters of reference marked thereon, which form a part of this specification.

This invention relates to that class of devices used as attachments to stoves or ranges for cooking or other purposes, when it is desirable to use simply the necessary fuel to complete the operation, without making so large a fire as is required to raise the temperature of the common cooking stove or range to a point which will enable it to accomplish this object; and the device will be found to be a great desideratum with families, especially during the summer months, when but a small amount of cooking is required, and it is desirable to have no fire which shall heat the room where the operation is in progress; and the invention consists in a certain cylindrical vessel provided with a grate at its bottom, and suitable openings for the exit of smoke or gas at its sides, which will now be fully described, and then pointed out in the claim.

Figure 1 is a perspective view of the device complete. Fig. 2 presents a vertical section. Fig. 3 is a plan of the grate. Fig. 4 is a view of the under side of the cover, showing the circular opening for the utensils, and the opening for the admission of air.

The cylinder A is of sheet or cast iron, and is securely attached at its upper end to an annular ring, B, of cast metal. These cylinders are made of such sizes as will allow them to pass through the ordinary openings in the tops of stoves or ranges, the ring B resting upon the top thereof, and serving to support

and retain the device in position. At the lower end of the cylinder is a flange, C, turned inward, thus becoming the support for a circular grate, D, which forms the bottom of the cylinder, which is also perforated with suitable openings *a* for the exit of smoke or gas, which passes off through the flues of the stove or range to the chimney. The cover E is of such dimension as to fill the opening in the top of the cylinder, and is itself provided with an opening, *b*, for the admission of air to the top of the fuel, when desired. This opening is closed by a slide, *c*, having an orifice through it of the same size as that in the cover, the slide moving in circular ways, and being retained in position by a dovetailed piece, *d*, which is riveted to the slide and locks it to the cover. The large circular opening in this cover E is closed by a supplementary cover, F, when not in use for cooking or other purposes. A bail, H, is attached to the annular flange B by two ears, *e e*, by which the whole attachment may be readily removed from the stove or range, when desired.

It will be obvious that this invention will allow the heating of water, making tea or coffee, or any of the minor operations of cookery, with the least possible amount of fuel, which is applied immediately under the article to be heated or cooked, thus avoiding the necessity of heating the whole stove or range, and raising the temperature of the room in which they are placed, as the surrounding air-spaces within the stove or range perform the function of a non-conductor, thus enabling it to be used in the warmest weather with scarcely a perceptible elevation of the temperature of the surrounding atmosphere.

Any ordinary finely-commminuted fuel may be used, as hard coal, charcoal, chips, or even sawdust; the apparatus being found to work well with either.

I am aware that portable stoves have been heretofore used, as may be seen in the patents of A. Magee, No. 40,570, and N. O. Bond,

No. 85,054; but I do not claim anything therein shown.

Having thus described my invention, I claim as new, and desire to secure by Letters Patent, the following:

A stove attachment consisting of the perforated cylinder A, provided with the flange B, bail H, grate D, and cover E, the latter having an opening, b, covered by the slide c,

all being combined and arranged as shown and described.

In testimony that I claim the foregoing as my own I hereunto affix my signature in presence of two witnesses.

AUGUSTUS BEAN.

Witnesses:

W.M. CHASE,
ANSON S. MARSHALL.
